UNITED STATES PATENT OFFICE.

FREDERICK S. WOODWARD, OF RICHMOND HILL, NEW YORK.

APPARATUS FOR ELECTROPLATING.

1,188,228.

Specification of Letters Patent. Patented June 20, 1916.

Application filed April 3, 1916. Serial No. 88,575.

To all whom it may concern:

Be it known that I, FREDERICK S. WOODWARD, a citizen of the United States, and a resident of Richmond Hill, Long Island, New York, have invented a new and useful Apparatus for Electroplating, of which the following is a specification.

My invention relates to electro-plating and is designed with a view of producing an apparatus that will deposit metal on the walls of deep pockets or recesses.

It is well known that, in a plating bath, the current will take the shortest path from the anode to the cathode and, consequently, the outside surface of the cathode will receive the deposit while little or no metal will be deposited in depressions or pockets in the cathode. By my improved apparatus the walls of deep pockets may be plated with as thick a coating of metal as the outside surface. I accomplish this result by completely segregating the anodes in a separate compartment of the electrolyte and by providing open-end tubes which communicate with this compartment. These tubes are so placed that they may be made to enter the pockets of the cathode without touching the walls of the pocket or recess. It is evident that, by this arrangement, the walls of the pocket opposite or adjacent to the outer end of the tubes are nearest the anode and afford the shortest path for the current from the anode to the cathode. Where the cavity has any appreciable depth I move the cathode during the plating operation so that the tubes will traverse the pockets and, if the movement be uniform, an even coating will be deposited on the walls of the pocket.

I have illustrated my invention by showing how it can be applied to the production of a radiator of the honeycomb type, such as is used on some automobiles.

In the description which follows reference is made to the accompanying drawings, in which:

Figure 1 is a plan view of a radiator; Fig. 2 is a side elevation of the same; Fig. 3 is a plan of my apparatus; Fig. 4 is a vertical sectional elevation on the line 4—4 of Fig. 3 and Fig. 5 is a diagrammatic side elevation showing a mold and two anode compartments.

The tank 1, of usual construction, is filled with the electrolyte up to the line 2. A horizontal partition 3 forms a compartment 4 for the anode 5. The partition has an open-

ing 6 into which is fitted, or which is covered by a plate 7.

The radiator 8, shown in Figs. 1 and 2, is a thin shell, having openings or pockets 9 extending through it from side to side. A mold 10 is made of the same form as the radiator. This may be of wax coated with plumbago or other conducting powder, or it may be made of any other suitable material, as a fusible metallic alloy—especially one of a low melting point. The mold is suspended by bolts 11 from a bar 12, which is notched at each end for guide rods 13—the guide rods extending upward from the partition 3. The bar 12 is secured on the lower end of a vertical plunger 14 which is guided in a support 15. This support extends across the tank and is mounted on side brackets 16. On top of the support 15 a shaft 17 is mounted in two bearing blocks 18. A heart cam 19, secured to the front end of the shaft, engages a roll 20 which is on the upper end of the plunger 14. The shaft 17 is revolved by power applied to a pulley 21 on the rear end of the shaft. It is evident, from this construction, that a uniform reciprocating movement will be given to the mold.

The plate 7 which covers the opening 6 in the upper wall of the anode chamber, is provided with open-end tubes 23. These tubes are spaced so that they correspond to the pockets of the mold and they, as well as the partition for the anode chamber, are preferably made of non-conducting material. It will be seen, by reference to Fig. 4, that the only path for the current from the anode to the mold is through the tubes 23 and that the shortest path is to the walls of the pockets of the mold which are adjacent to the upper end of the tubes. By revolving the shaft 17 the mold will be reciprocated, as already stated, and the tubes will traverse the pockets of the mold and the motion being uniform, an even coating will be deposited on the inside of the pockets. By turning the shaft very slowly but one traverse movement would be necessary, but if the solution does not work uniformly during the entire operation, the plating would be irregular or uneven. By turning the shaft fast enough so that the mold will be reciprocated frequently during the plating operation an even coating will be obtained, even though the solution does not work uniformly. When sufficient thickness is obtained in the pockets the plate with the

tubes can be taken out to complete the shell on the outside of the mold.

To prevent the electrolyte in the anode chamber becoming exhausted I keep up a circulation by a pump. This may be of any approved type, the one shown in the drawings, 24, being of the piston variety. It is operated by a connecting rod 25 which is driven by a crank arm 26. This crank arm 10 is secured to the front end of a shaft 27 which is mounted in bearings 28 on a bracket 29—movement being given the shaft by power applied to a pulley 30 on its rear end. The electrolyte enters through a port 15 31 and is forced into the anode chamber through the valve 32. This causes a circulation through the tubes and pockets of the mold, prevents bubbles forming and facilitates the deposition of the metal.

20 In Fig. 5 I have shown, in diagrammatic elevation, a mold 33 (having a support 34 which is attached to a bar 35) and two anode boxes 36 with two sets of tubes 37. When the mold is in the position shown in 25 Fig. 5 most of the deposit will go on the right hand side of the mold. By moving the mold to the right both sets of tubes will traverse the pockets, depositing metal as they go, and when the limit of movement is 30 reached, the deposit will be made almost entirely on the left hand surface of the mold. By handling the mold in this manner, between two sets of tubes, the work is facilitated and a smooth deposit on the sides is 35 obtained. When a sufficient thickness of metal has been deposited the work is taken out of the bath, the bolts 11 are removed and the mold itself melted out, leaving a thin, hollow shell, extremely light and 40 water tight.

What I claim is:

1. In a pocket or recess electro-plating apparatus, the combination of the following elements: an electrolyte; an anode compartment in said electrolyte; a tubular projection from said anode compartment, which is adapted to enter the pocket or recess of the cathode or object to be plated and means for causing said tube to traverse said recess or pocket during the plating operation.

2. In a pocket or recess electro-plating apparatus, the combination of the following elements: an electrolyte; an anode compartment in said electrolyte; a tubular projection communicating with said compartment and adapted to enter said pocket or recess of the cathode; means for moving the cathode to cause said tube to traverse said recess during the process of plating and means for forcing the electrolyte into said anode compartment.

3. In a pocket or recess electro-plating apparatus, the combination of the following

elements: an electrolyte; an anode compartment in said electrolyte having a removable 65 wall portion; an open-end tube mounted in said removable wall portion and adapted to enter the pocket of the cathode and means for reciprocating the cathode during the plating operation to cause said tube to traverse said pocket.

4. In a pocket or recess electro-plating apparatus, the combination of the following elements: an electrolyte; means for segregating the anodes in a separate chamber or 75 compartment in said electrolyte; an open-end tube projecting from said compartment and adapted to enter the pocket of the cathode; a pump for forcing the electrolyte into said anode chamber and reciprocating 80 means to cause said tube to traverse said pocket during the plating operation.

5. In a pocket or recess electro-plating apparatus, the combination of the following elements: an electrolyte; a partition across 85 said electrolyte which separates the anode from the cathode; an open-end tube mounted in said partition which extends into the cathode electrolyte and which is adapted to enter the pocket or recess of the 90 cathode; reciprocating means to cause said tube to traverse said pocket during the plating operation and means for forcing the electrolyte from the cathode side to the anode side of said partition.

6. In a pocket or recess electro-plating apparatus, the combination of the following elements: an electrolyte; an anode compartment in said electrolyte; an open, tubular projection from said anode compartment 100 which is adapted to enter the pocket of the cathode; reciprocating means to cause said tube to traverse said pocket during the plating operation and guide connections to secure the proper alignment or registering 105 of said tube with said pocket.

7. In a pocket or recess electro-plating apparatus, the combination of the following elements: an electrolyte; an anode compartment in said electrolyte; an open, tubular 110 projection from said anode compartment which is adapted to enter the pocket or recess of the cathode; means for reciprocating the cathode to cause said tube to traverse said pocket during the plating operation and guide connections between the cathode and said anode compartment which are adapted to properly align or register said tube with said pocket or recess.

In testimony whereof I affix my signature 120 in presence of two witnesses.

FREDERICK S. WOODWARD.
